UNITED STATES PATENT OFFICE

170,408

HEXAGON CAPPED NUT

Otto Gries, New Rochelle, N. Y.

Application February 18, 1952, Serial No. 18,570

Term of patent 14 years

(Cl. D54—7)

To all whom it may concern:

Be it known that I, Otto Gries, a citizen of the United States, now residing at New Rochelle, in the county of Westchester and State of New York, have invented a new, original, and ornamental Design for a Hexagon Capped Nut, of which the following is a specification, reference being had to the accompanying drawing, forming part thereof.

Fig. 1 is a side elevation view of a hexagon capped nut, showing my new design.

Fig. 2 is a plan view of the structure as seen in Fig. 1.

Fig. 3 is a bottom view of the structure as seen in Fig. 1.

I claim:

The ornamental design for a hexagon capped nut, as shown.

OTTO GRIES.
